UNITED STATES PATENT OFFICE.

WILLIAM H. SHEPPARD, OF WORCESTER, MASSACHUSETTS, ASSIGNOR TO SHEPPARD ENVELOPE COMPANY, OF WORCESTER, MASSACHUSETTS, A CORPORATION OF MASSACHUSETTS.

ENVELOPE MACHINE.

Application filed March 11, 1921. Serial No. 451,518.

To all whom it may concern:

Be it known that I, WILLIAM H. SHEPPARD, of Worcester, in the county of Worcester and State of Massachusetts, a citizen of the United States, have invented a new and useful Improvement in Envelope Machines, of which the following is a specification.

My improvement relates to the means for discharging the envelope from the folding box, which is especially useful in that class of machines in which the envelope is discharged laterally or edgewise from the box, as for example under the seal flap folder 15 as shown in Letters Patent No. 648,674, dated May 1, 1900.

In the machine of that patent the envelope is discharged horizontally and is delivered to a driver located on lower level 20 than the folding box, shields or guides being provided outside the folding box to change the path of movement of the envelope from a horizontal to a more nearly vertical path. In a machine embodying my invention the 25 rear edge of the envelope is lifted while in the box and the envelope is discharged therefrom in a direction at an angle to the bottom of the box. In this way the ejecting means will surely engage the envelope 30 to discharge it and there will be no danger of the folded envelope sticking to the folding bed because of the pressure of the folders or because of suction, etc., so that the ejectors will ride over it, such as might 35 be the case where the ejectors reciprocated in a straight line across and in close proximity to the surface of the folding bed.

My invention will be understood by reference to the drawings in which it is 40 shown in its preferred form.

Figure 1 is a side elevation of mechanism embodying my invention, the folding box and table being in longitudinal section.

Fig. 2 is a section on line 2-2 of Fig. 3, 45 and

Fig. 3 is a plan.

In the patent above referred to, when the seal flap folder lifts after folding the envelope, the pusher slides the envelope out 50 under the seal flap folder which is undercut for the purpose.

In my improvement, the bed of the folding box is slotted to allow kickers to pass

through it and lift one edge of the envelope so that it is held at an angle to the bottom 55 of the box and then push it under the seal flap folder.

Only so much of an envelope machine of the plunger type is shown as is necessary to explain my invention.

1 is a portion of that part of the frame which carries the folding box, being the bed thereof. On the edge of the folding box are mounted the folders in the usual way, two of which 3 and 4 are shown without 65 their mountings or operating mechanisms which may be of any ordinary character, the folder 3 being undercut as shown in said patent.

The folding bed 2 of the folding box is 70 slotted as at 5 and in the slots lie the kickers 6 which comprise two somewhat hook-shaped arms mounted on a cross bar 7. The cross bar 7 forms part of a bell crank lever system 8, the lower end of which is hinged 75 to a rocking lever 9 pivoted below the frame 1 and operated by a cam 10 through the cam lever 11 on shaft 12 and link 13 connected with the arm 14 on sleeve 15 mounted on shaft 16. This sleeve 15 also carries an arm 80 17 connected by link 18 with the rocking lever 9 preferably near its middle. By this means the kickers are lifted to lift the edge of the folded envelope 28.

The motion of the kickers is also controlled by the cam 19 through the cam lever 20 on shaft 12, which cam lever 20 is connected by link 21 with an arm 22 on sleeve 23 also on shaft 16. Sleeve 23 also carries an arm 221 which is loosely connected (see 85 Fig. 2) by a link 24 with a carriage 25 running on rods 26 mounted below the frame 1 so that the carriage is reciprocated from the cam 19. The carriage is connected by link 27 with the bell crank 8 between its angle and 90 the connection of the rocking arm 9 with link 18. By means of these two cams the kickers are not only given an upward movement to lift the envelope 28, but their upper ends are drawn back into a recess 41 in the 95 folder, on reaching which they are pulled out from under the envelope through the opening under folder 4, catching the envelope before it can fall onto the folding bed after 100 which they are returned to their original 105 position. See Fig. 1 where the movements

are indicated in dotted lines, the envelope being indicated at 28 in full and dotted lines.

29 is a friction roll stop which guides the 5 kickers in co-operation with the rear surface thereof. There are two of these friction rolls, one for each kicker. One only is shown in the drawing.

The loose connection between the carriage 10 25 and the rod 24 is shown in its preferred form in Fig. 2. A spring 30 suitably attached at one end to the rod 24 and at the other end to the carriage 25 keeps these parts 15 normally in engagement, but allows a little delay in the return of the carriage to its normal position.

It will be noted that this construction allows the bed 2 to be in one piece, the slots 5 passing only partially across it thus allowing its outer edge to be unbroken, and giving it the usual continuous rim over which the folders will reach in their action of giving a sharp clean fold to the envelope.

It will also be noted that the motion of the 25 kickers is at first a substantially vertical motion to lift the edge of the folded envelope after which they engage the edge of the envelope and are moved forward and downward pushing the envelope over the edge of 30 the bed and then while still in upright position being withdrawn to their original position.

In Fig. 1 the kickers are shown in full 35 lines in their position during the folding operation after which the kickers are moved up, lifting the edge of the envelope 28, and retreat into the recess 41 and then start forward pushing the envelope out under the folder 3 toward the drier or other mechanism.

40 Other means of operating the kickers to perform the desired function will occur to those skilled in the art, my invention comprising mainly the use of kickers operated to lift one edge of the work and later discharge it in the manner described.

Moreover, my invention is useful in ma-

chines of other kinds than envelope machines, where a piece of work is to be moved from a bed or plate to another mechanism or 50 receptacle.

What I claim as my invention is:—

1. In a machine of the kind described, a folding mechanism comprising a bed having a solid edge, said bed having slots therein and means adapted to pass through said slots to engage the under side of the work and lift it off said bed and thereafter to engage the edge of said work and push it edgewise off said bed. 55

2. A machine of the kind described comprising a bed having a solid edge and slots passing through the body of said bed, means for ejecting work from said bed comprising kickers located in said slots and means whereby they are lifted substantially vertically through said slots near one edge thereof and then in a general horizontal direction across said bed and downward and back to their original position. 60

3. In a machine of the kind described, a folding mechanism comprising a folding bed having slots therein, kickers adapted to move in said slots, and means for moving said kickers comprising cams and connections between said cams and said kickers whereby said kickers will be lifted to lift one edge of the folded work, then withdrawn from under the work and then moved across the face of the bed and returned downward to 70 their first position. 75

4. In an envelope machine of the kind described, a folding mechanism comprising a slotted folding bed and folders, kickers normally located below said folding bed and within its projected area, and means for lifting said kickers through the slots in said bed to lift the folded envelope, then moving said kickers rearwardly from under the envelope to engage its lifted edge and then moving said kickers forward to eject the envelope from said bed and finally moving said kickers into their normal position. 85 90

WILLIAM H. SHEPPARD.
